MOUNTING FOR ELECTRICAL APPARATUS

Edward H. Jones, Summit, N. J., assignor to Bell Telephone Laboratories, Incorporated, New York, N. Y., a corporation of New York

Application August 14, 1931, Serial No. 556,953

12 Claims. (Cl. 173—328)

This invention relates to mountings for electrical apparatus and more particularly to cushion type sockets for electron discharge devices.

The electrical characteristics of electron discharge devices are largely dependent upon the space relation of the several electrodes of the devices. Any changes in this relation, particularly such changes as are occasioned by mechanical and acoustic shocks to which the device may be subjected during operation, produce objectionable microphonic disturbances in the output of the device which result in unfaithful and distorted translation of the input signal. Shocks of great magnitude often damage the electrode structures in electron discharge devices and in particular cause rupture of the fragile filament wires in such devices embodying filamentary cathodes.

An object of this invention is to eliminate microphonic disturbances in the output of an electron discharge device and to translate signal voltages applied to such a device faithfully and without distortion.

Another object of this invention is to protect sensitive electrical apparatus against deleterious shock.

A further object of this invention is to simplify the assembly and to expedite the manufacture of cushion type sockets for electrical apparatus.

The features of this invention are exemplified in one embodiment in a cushion type socket for electron discharge devices, comprising a stationary support, a movable socket member within the support and adapted to receive the terminal prongs on an electron discharge device or other apparatus, and a plurality of conducting members resiliently supporting the movable socket within the support. Each of the conducting members comprises a contact or socket portion for gripping the terminal prong of an electron discharge device or similar apparatus, a slotted terminal portion secured to the support and extending outwardly therefrom, and an intermediate portion including spaced arms and a resilient loop portion. One of the spaced arms is provided with a slot and the other of the arms is provided with a tongue projecting into the slot for limiting the excursions of the movable socket member with respect to the support. The vibration of the movable socket member may be damped by suitable means as for example a coating of absorbent material upon the resilient loop of the intermediate portion of the conducting members.

The invention will be understood more fully

from the following detailed description with reference to the accompanying drawing in which:

Fig. 1 is a plan view of a mounting for electrical devices constructed in accordance with this invention with portions broken away, and partly in section to show the form and positioning of a conducting member;

Fig. 2 is a cross-sectional view along line 2—2 of Fig. 1;

Fig. 3 is an exploded view of a mounting in accordance with this invention with portions broken away, and partially in cross-section to show details of assembly more clearly;

Fig. 4 is a detail perspective view of a unitary contact and terminal member in accordance with a feature of this invention; and

Fig. 5 illustrates a metallic stamping from which the unitary contact and terminal member shown in Fig. 4 is formed.

Referring now to the drawing, a mounting such as a cushion socket for electron discharge devices, in accordance with this invention comprises a cup-shaped stationary support 10 of insulating material such as laminated phenol fibre, and a movable socket 11, likewise of an insulating material, such as a phenol condensation product, centrally positioned and resiliently supported within the cup-shaped support 10 by a plurality of electrically conductive members or stampings 12. The number 12 is used to designate the conductive member, shown in the drawing, for example, Figs. 4 and 5, as a whole.

The movable socket 11 comprises a cylindrical body portion 13 provided with a plurality of uniformly spaced recesses 14 communicating each with a corresponding radially extending slot 15 in the circular wall of the body portion 13, and with the usual apertures 16 for receiving the terminal prongs of an electron discharge device or similar apparatus. A circular insulating plate 17 is secured to the body portion 13 in any suitable manner, as by an eyelet 18, to close the open end of each of the recesses 14 and to provide a rigid substantially closed unitary element.

Each of the conductive stampings 12, which are preferably of phosphor bronze, as clearly shown in Figs. 4 and 5, comprises a contact portion 19 for gripping a terminal prong of an electron discharge device or the like, an outwardly extending terminal portion 20 provided with a slot 21 for expediting the attachment of a conductor or the like to the terminal portion 20, and an intermediate portion 22 integral with the contact and terminal portions 19 and 20, respectively.

The intermediate portion 22 includes two par-

allel arm portions 23, 24 and a resilient loop portion 25. Each contact portion 19 consists of two similar parallel sections, each provided at one edge with a curved lip or outwardly bulged portion 26 for guiding a terminal prong and with a tab 27 for insuring positive gripping of the terminal prong. Each of the parallel sections defining the contact portion 19 is formed with an integral extension or tongue 28 which projects through a slot or an aperture 29 in the arm 24.

In the assembly of the mounting each of the terminal portions 20 is positioned on a seat 30 on the rim of the cup-shaped support 10 and is clamped in place by pairs of bent tabs or downwardly extending projections 31, 32 which grasp opposite walls of the support in channels 33 adjacent the seats 30. The contact portions 19 are positioned one within each of the recesses 14 in axial alignment with a corresponding one of the apertures 15 with the curved lips 26 contiguous with the periphery of the corresponding aperture 16. The contact portions 19 abut against the faces of the recesses in the body portion 13 and against the inner face of the plate 17. The end portions 34 of each of the parallel sections forming the contact portion 19 of each conductive stamping 12 frictionally engage the walls of their respective slots 15 and securely lock the contact portion 19 in position. One of the tongues or extensions 28 is bent toward the other tongue or extension as shown at 35 in Fig. 1 to definitely space the end portions 34 of each of the parallel sections forming the contact portion 19 of each stamping 12. Excessive lateral displacement of the contact portions 19 is further prevented by the walls of its corresponding recess 14.

A cover plate 36, preferably of insulating material, such as a phenol condensation product, is provided with a centrally disposed aperture 37 to allow free passage of the movable socket 11 and is secured to the support 10, as by hollow eyelets 38, to clamp the terminal portions 20 of the conductive stampings 12 in the seats 30. The eyelets 38 are adapted to allow passage of screws or the like for securing the support 10 to a panel or other mounting member.

The loop portions 25 of the stampings 12 are universally flexible to allow substantially free vibration of the movable socket portion 11 and thereby effectively protect a device, such as an electron discharge device, against acoustic and mechanical shocks. The cooperative tongue 28 and slot 29 arrangement prevents excessive lateral, longitudinal or rotative displacement of the movable socket 11 and also prevents deleterious distortion of the resilient loops 25.

Because of the resiliency of the loop portions 25, the movable socket 11 may oscillate for an appreciable length of time if it is set in vibration. This oscillatory movement may deleteriously affect the operation of a device, such as an electron discharge device, and impair the efficiency thereof. In accordance with a feature of this invention this defect is circumvented by damping the vibration of the movable socket 11. This may be accomplished in one way by coating a section of the resilient loop portions 25 of the stampings 12 with a vibration damping material or absorbing medium, such as an asphalt emulsion, rubber solution or the like.

Although in the specific embodiment of the invention described hereinabove and shown in detail in the accompanying drawing, the movable socket 11 is adapted to accommodate a device

having four terminal prongs, it may readily be adapted to receive a greater or lesser number of terminal prongs. Other modifications may, of course, be made in the structure shown without departing from the scope and spirit of this invention as defined in the appended claims.

What is claimed is:

1. A mounting for electrical apparatus comprising a stationary member, a movable socket member, and means for resiliently supporting said socket member from said stationary member, said means having portions cooperating mechanically to finally limit displacement of said socket member in several directions.

2. A cushion type mounting for electrical apparatus comprising a recessed base, a movable socket member positioned within said base and adapted to support said apparatus, and members resiliently supporting said socket within said base, said members having interfitting portions adapted to abut to limit axial movement of said socket.

3. A cushion type mounting for electrical apparatus comprising a recessed base, a socket member disposed within said base, and a plurality of flexible members supporting said socket member within said base, said members including juxtaposed relatively displaceable portions, one of said portions having a slot, and the other of said portions having a longitudinally and laterally rigid tongue projecting into said slot for limiting relative displacement of said portions.

4. A mounting for electrical apparatus comprising a stationary base, a socket member including a body having spaced recesses therein and apertures communicating with said recesses and adapted to receive terminal prongs on said apparatus, and a plurality of conductive members for mounting said socket member from said base, each comprising a terminal portion secured to said base, an expansible contact portion disposed within one of said spaced recesses in alignment with the corresponding aperture, and juxtaposed portions integral with said terminal and contact portions and adapted to engage each other to limit the lateral and longitudinal movement of said socket member.

5. A mounting for electrical apparatus comprising a cup-shaped base, a cylindrical socket member disposed within said base including a cylindrical body portion having spaced recesses therein, apertures in one wall communicating with said recesses and adapted to receive terminal prongs on said apparatus, and slots extending radially outwardly from said recesses, and a plurality of conductive members supporting said socket member within said base, each of said conductive members comprising a terminal portion secured to said base, a contact portion, and an intermediate resilient portion including an arm provided with an aperture, said contact portion comprising substantially parallel plate sections positioned within one of said recesses and cooperatively yieldable to securely grasp a terminal prong on said apparatus, a shoulder frictionally engaging a wall of said one recess, and a tongue extending from one of said plate sections and projecting into the aperture in said arm.

6. In a mounting for electrical apparatus, a unitary electrically conductive member comprising a terminal portion, a contact portion for engaging a terminal prong of said apparatus, said contact portion being freely displaceable with respect to said terminal portion and a portion connecting said terminal and said contact portions,

- two of said portions having interfitting means for finally limiting the displacement of said contact portion in at least two planes.
7. In a mounting for electrical apparatus, a unitary terminal and contact member comprising a terminal portion, a contact portion adapted to engage a terminal prong of said apparatus, and an intermediate portion including spaced substantially parallel arms and a resilient loop portion connecting said arms, one of said arms being provided with an aperture, and a rigid tongue extending from said contact portion and projecting into said aperture.
8. In a mounting for electrical apparatus, a unitary conductive member comprising a terminal portion having integral extensions for engagement with a support, a contact portion including two substantially parallel sections adapted to grip a terminal prong on said apparatus, and an intermediate portion including a substantially universally yieldable portion and including a portion having an aperture therein, and extensions from said parallel sections loosely disposed in said aperture.
9. A mounting for electrical apparatus comprising a stationary support, a movable socket member, means for resiliently mounting said socket member from said support, and a coating of a vibration damping substance on said means.
10. A mounting for electrical apparatus comprising a stationary base, a movable socket member and metallic members resiliently mounting said socket member from said base, and a coating of an asphalt emulsion on said metallic members.
11. A mounting for electrical apparatus comprising a base, a cylindrical socket member, a plurality of conductive members resiliently mounting said socket member within said base, each of said conductive members including a terminal portion secured to said base, a contact portion mounted on said socket member, and an intermediate resilient portion, and a coating of vibration damping material on said intermediate resilient portion.
12. A vacuum tube socket comprising a base member, a socket member and metallic members, one for each terminal, said metallic members serving as the support for the socket member and being provided with means for limiting the vertical as well as the horizontal movement of the socket member when a tube is inserted in or withdrawn from said socket member.
